F16M 13/02

The ornamental design for a case for portable electronic computing device, as shown and described.

See application file for complete search history.

DESCRIPTION

(56) **References Cited**

FIG. 1 is a front perspective view of a case for portable electronic computing device showing our new design.

U.S. PATENT DOCUMENTS

FIG. 2 is a rear perspective view thereof.

D681,641 S	5/2013	Van Den Nieuwenhuizen et al.
D721,080 S	1/2015	Mecchella et al.
D724,093 S	3/2015	Dong
D727,915 S	4/2015	Mecchella et al.

D812,620 S	3/2018	Cheng
D816,087 S	4/2018	Fenton et al.

FIG. 3 is a front elevational view thereof.

FIG. 4 is a rear elevational view thereof.

FIG. 5 is a top plan view thereof.

FIG. 6 is a bottom plan view thereof.

FIG. 7 is a left elevational view thereof; and,

FIG. 8 is a right elevational view thereof.

The broken lines in the drawing figures form no part of the claimed design and depict portions of the case for portable electronic computing device that form no part of the claimed design.
